FIG. 9

Inventor

William W. Watson

By S. Arthur Baldwin,
Attorney

UNITED STATES PATENT OFFICE.

WILLIAM W. WATSON, OF JAMESTOWN, NEW YORK.

WINDOW SCREEN.

Application filed January 9, 1922. Serial No. 528,072.

To all whom it may concern:

Be it known that I, WILLIAM W. WATSON, a citizen of the United States, residing at the city of Jamestown, in the county of Chautauqua and State of New York, have invented certain new and useful Improvements in Window Screens, of which the following, taken in connection with the accompanying drawings, is a specification.

- 10 The invention relates to screens adapted for use in connection with pivoted ventilator sash hinged at or near their center so that when turned to the open position, they extend both outward and inward, thereby requiring a pair of screens, one above and one below the central portion of said pivoted ventilator sash and on opposite sides of the window sash; and the object of the improvement is to provide screens adapted to fill the 20 upper and lower portions of the ventilator sash openings, said screens being hinged to the pivotal ventilator sash so as to automatically move upward and downward with said pivotally mounted ventilator sash when 25 turned to or from the closed position, said screens being supported and controlled by strips hinged to the screens and to the ventilator sash to thereby substantially close the opening between the screen and ventilator sash, and at the same time slidably 30 operate one or more of said screens; and the invention consists in the novel features and combinations hereinafter set forth and claimed.

- 35 In the drawings, Figure 1 is an elevation of a portion of a window sash having the improved screens mounted therein, the pivoted ventilator sash being shown in the open position. Fig. 2 is a crosswise sectional view at line 2-2 in Fig. 1 showing the preferred arrangement of the sliding upper screen and its connection to the window sash. Fig. 3 is a lengthwise sectional view at line 3-3 in Fig. 1 of the pivoted ventilator sash 40 in the semi-open position showing the position of the different parts in said semi-open position; and Fig. 4 is also a lengthwise sectional view at line 3-3 in Fig. 1 showing the pivoted ventilator sash in the full open 45 or right angle position with the hinged closure strip vertically supporting and closing the space between the lower edge of the sliding screen frame and the cross bar of the pivoted ventilator sash; and Fig. 5 is likewise a sectional view at said line 3-3, slide way 17 when inserting the same, there-

with the pivoted ventilator sash in the closed position. Fig. 6 is a side elevation of a portion of the window sash with the lower portion of the screen slide attached thereto and the screen slidably mounted therein, the central portion of the pivoted ventilator sash being shown in the closed position. Fig. 7 is a detailed elevation of one of the pivoting hinges for the ventilator sash, showing the corner of the lower fixed or stationary screen, the ventilator sash being in the closed position. Fig. 8 is a plan view of the hinged closure strip for the crosswise opening between the upper slidably mounted screen and the pivoted ventilator sash. Fig. 9 is a lengthwise sectional view of the window sash and the pivoted ventilator sash at line 3-3 in Fig. 1, showing the upper and lower screens in edgewise elevation, hingingly connected by closure strips 75 to the pivoted ventilator sash. Fig. 10 is an elevation of the central edge portion of the pivoted ventilator sash showing the additional cross bar or rail as attached to the pivotal ventilator sash, the pivot pin being 80 shown on the outer side of said sash about midway between the two cross rails or bars.

Like characters of reference refer to corresponding parts in the several views.

The numeral 10 designates the window sash which has the ventilator sash 11 pivotally mounted therein by means of the hinges 12 at each side of the central portion of said ventilator sash 11.

As shown in Fig. 3, the lower portion of the ventilator sash swings outward and the upper portion swings inward in opening the ventilator sash 11. The lower opening 13 is usually screened by the lower stationary or fixed screen 14, which screen is preferably made of the tubular sheet metal screen construction as shown in my Letters Patent Number 956,239 of April 26, 1910. The ventilator sash 11 has the angular sheet metal crosswise strip 15 to close the space between the upper edge of the fixed screen 14 and the ventilator sash 11 in swinging the same.

The numeral 16 designates the upper screen which is slidably mounted in the ways 17 on the outer side of the window sash as shown in section in Fig. 2, said window screen 16 having sufficient play or space 18 at each side mounted in the ways 17 to permit crowding the window screen 16 into one slide way 17 when inserting the same, there-

by entering the opposite sliding way 17. The window screen is held firmly in the centered position by the hinges as hereafter described. The sliding ways 17 are firmly attached to the window sash preferably by means of striking out lugs 19 which have the holes 29 therein, as shown in the detail in Fig. 2; so that an attaching screw 21 can be inserted through said hole 20 into the frame 10, thereby rigidly attaching said ways on said frame. This attachment can be made before the insertion of the screen 16 into the ways 17.

In order to close the space 22 between the lower edge of the sliding screen 16 and the ventilator sash 11, a closure strip 23 is hinged to said ventilator sash preferably to the cross rail 24 of said sash 11 by means of the hinge strap pieces 25 at spaced intervals along the rail 24 for the lower edge of said closure strip 23. The upper edge is similarly hinged at spaced intervals by hinges 26 to the under side of the edge of the sliding screen frame 16. It is now apparent that the screen 16 will be automatically moved upward and downward by the swinging of the ventilator sash 11, the closure strip moving backward and forward from the vertical to the inclined position as shown in the drawings, yet constantly keeping said space 22 closed.

In mounting the sliding screen 16, in the window sash, on high buildings, it is apparent that the screen 16 must be mounted from the inner side of the sash 10. As hereinbefore stated, the sliding ways 17 may be attached from the inner side of the window sash 10, and there is sufficient leeway in said sliding ways 17 for the screen 16 so that it can be inserted into the sliding way 17 at one side, and may be drawn into the opposite sliding way. To conveniently accomplish this, a handle 27 is provided which is insertable in the holes 28 in the tubular screen side to thereby draw the screen 16 into said opposite sliding way 17 and adjust the screen to the central position shown in Figs. 1 and 2 in its relation to the sliding ways 17. The hinged closure strip 23 is attached to the screen frame 16 before inserting said screen in the sliding ways 17, and the hinged strap pieces 25 are attached to the cross rail 24 of the ventilator sash 11 after said screen 16 is inserted in the sliding ways 17, thereby centering and holding said screen 16 in the centered position so that it can move freely upward and downward and cannot be removed from the sliding ways 17 without the withdrawal of the attaching screws for the hinged strap pieces 25.

The ventilator sash 11 has the hinge plates 12 attached one to the window sash 10 and the other to the ventilator sash 11 at each side of said sash and extending inward as

shown in Figs. 3, 4, 5, and 6, thereby supporting the ventilator sash 11 so that it is quickly and easily controlled.

In certain forms of pivoted ventilator sash, it is desirable to slidably mount both the upper and lower window screens so that both of said screens will automatically move upward and downward with the pivotal swinging of the ventilator sash. In order to accomplish this purpose, a cross rail or bar 31, preferably channel-shaped, is provided on the pivoted ventilator sash 11 at a proper distance from the ventilator sash pivot 38, as shown in Figs. 9 and 10, to which a crosswise closure strip 32 is hingingly connected on its upper edge, the lower edge being hinged to the screen 33 which is slidably mounted in ways 34 on the inner side of the window sash 10 in substantially the same manner that the screen 16 is mounted and hingingly controlled on the outer side of the window sash 10, except that the screen 33 hangs on the hinging closure strip 32. The ends of the channel rail 31 are attached to the sides of the ventilator sash 11, as shown at 35 in Fig. 10, at a proper distance from the ventilator pivot 38. The rail 31 extends down to the glass 30 in said sash to thereby close the opening between the cross rail 31 and the glass 30, and at the same time brace said cross rail and strengthen the same. If the cross bar 24 is not present or not located properly, a cross bar similar to 31 and similarly used to operate the outer screen 16 may be used.

The crosswise closure strips 23 and 32 are preferably provided with tubular edges and cut-out portions to receive therein the tubular attaching strap pieces 25-26 and 36-37 on their upper and lower edges to receive therethrough the hinge pins 29 for attachment to the sash cross rails and the screen frame. The uniform width of the sliding ways 17 and 34 is permitted by the double hinged strips 23 and 32 so that while the cross rails 24 and 31 swing backward and forward in opening and closing the ventilator sash 11, such radial movement is cared for by said hinge strips 23 and 32.

What is claimed as new is:

1. In a window of the class described, the combination of a window sash, a ventilator sash pivotally mounted in said window sash, a lower screen attached to the inner side of said window sash, vertical uniform ways on said window sash, a screen slidably mounted in said ways, and a filling strip hinged to the bottom rail of said slidably mounted screen and to a cross rail of said ventilator sash to raise and lower said screen with the pivotal swinging of said ventilator sash and to close the space therebetween.
2. In a window of the class described, the combination of a window sash, a ventilator sash pivotally mounted in said window sash,

parallel vertical ways on the outer side of said window sash, a screen slidably mounted in said ways, said ways wider apart than the width of said screen to insert said screen 5 from the inner side of said window sash, a filling strip hinged to the lower edge of said screen and to the central portion of said ventilator sash to center said screen in said ways to raise and lower said screen 10 and to close the space between said screen and ventilator sash in all positions.

3. In a window of the class described, the combination of a window sash, a ventilator sash pivotally mounted in said window sash, 15 parallel vertical channel ways on the outer side of said window sash above said pivotally mounted sash and similar parallel vertical channel ways on the inner side of said window sash below said ventilator sash, window screens slidably mounted in said ways 20

above and below said pivotally mounted sash, a filling strip hinged to the bottom rail of said upper slidably mounted screen and to a cross rail of said ventilator sash, a second cross rail mounted on said ventilator sash a 25 spaced distance above said first cross rail, and a second filling strip pivotally hinged to the upper cross rail of said screen and to said upper cross rail mounted on said ventilator sash said strips acting to raise and lower 30 said screens with the pivotal swinging of said ventilator sash and to close the spaces therebetween.

In testimony whereof I have affixed my signature in the presence of two witnesses.

WILLIAM W. WATSON.
